UNITED STATES PATENT OFFICE.

HARRY K. RAYMOND, OF AKRON, OHIO, ASSIGNOR TO THE B. F. GOODRICH COMPANY,
A CORPORATION OF NEW YORK.

DESIGN FOR A TIRE.

● 44,385.

Specification for Design.

Patented July 22, 1913.

Application filed March 7, 1912. Serial No. 682,264. Term of patent 7 years.

To all whom it may concern:

Be it known that I, HARRY K. RAYMOND, a citizen of the United States, residing at Akron, in the county of Summit, State of Ohio, have invented a new, original, and ornamental Design for Tires, of which the following is a specification, reference being had to the accompanying drawing, forming a part hereof.

The figure is a perspective of a section of a tire showing my new design.

I claim:

The ornamental design for a tire as shown.

HARRY K. RAYMOND.
